HEAD FOR DOLLS

John R. Gammeter, Akron, Ohio, assignor to The
 B. F. Goodrich Company, a corporation of New
 York

Application July 5, 1932, Serial No. 620,747

7 Claims. (Cl. 46—40)

This invention relates to heads for dolls, and more especially it relates to dolls' heads having movable, sleeping eyes.

- The invention is of primary utility in doll heads made of resilient material, such as molded rubber composition, in that it permits flexure of the head between the eyes without impairing or straining the eye-operating mechanism, yet provides sympathetic movement of the two eyeballs.
- 10 The chief objects of the invention are to provide a doll head having sleeping eyes wherein there is relatively independent but sympathetic movement of the eyeballs; and to provide a doll head of the sleeping eye type that permits flexure 15 of the head between the eyes. Other objects will be manifest.

Of the accompanying drawing,

- Figure 1 is a section, in two different vertical planes, of a doll head in upright position and 20 embodying the invention in its preferred form; and

Figure 2 is a section on the line 2—2 of Figure 1.

- Referring to the drawing, 10 is a doll's head 25 that is made of resilient material such as vulcanized rubber composition. The head 10 is formed with the usual eye openings 11 which may be of almond shape, and back of each eye opening is a cylindrical socket 12 formed by a 30 circular wall 13 that is integral with the structure of the head and circumscribes said eye opening. Mounted in each socket 12 is a tubular, metal thimble 14, the forward end of which is formed with an inwardly turned flange 15 that is 35 disposed immediately behind the structure of the head that surrounds the eye opening 11, to reinforce the same. The flange 15 is tapered or beveled toward its free margin so as to permit an eyeball 17 to be positioned close to the opening 11. The thimble may be cemented in place 40 in the socket 12, or it may have a force fit therein and be held in place by the tension of the rubber wall 13.

- 45 The eyeballs 17 are pivotally mounted upon respective pivot rods 18, the latter extending transversely of the respective thimbles 14, parallel to the long axis of the eye openings 11. The pivot rods 18 extend through suitable apertures in opposite side walls of the respective thimbles, and are retained therein by the walls of the sockets 12 when the thimbles are mounted in the latter. Preferably the thimble-wall about said apertures is slightly recessed as shown at 50 19, 19 so that the ends of the pivot rods do not

project beyond the outside diameter of the thimbles.

The eyeballs 17 may be made of any suitable material such as metal or porcelain, and on the front thereof are decorated in the usual manner to represent the iris of the eye and a flesh colored lid portion, the latter being visible through the openings 11 when the eyeball is in the sleeping position indicated in broken lines in Figure 1.

5 In order to cause the eyeballs to move angularly 10 on their pivot rods 18 when the head is tilted, there is provided a counterweight 20 that is mounted upon a resilient U-shaped member 22 that has its end portions secured in the respective eyeballs 17, at the rear thereof, said resilient 15 member preferably consisting of a helically coiled spring as shown. Internally of the head structure 10, at the chin thereof, is formed a projecting abutment 23 that is so positioned as to be engaged by the counterweight 20 when the head 10 20 is in upright position, whereby the open position of the eyeballs is accurately determined.

Being flexible, the resilient connection 22 between the eyeballs permits limited independent relative movement of the latter, which movement, 25 however, will be more or less sympathetic because of said connection. Because there are no rigid connections between the eyes of the doll, the eye structure is especially applicable to doll heads made of flexible material such as rubber, since 30 there will be no straining or permanent distortion of the eye structure due to flexing or bending of the head.

Modification may be resorted to within the 35 scope of the appended claims which are not 35 limited wholly to the specific construction shown and described.

What is claimed is:

1. A head for dolls comprising a pair of eyeballs independently journaled therein, and a 40 helically wound spring having its end portions connected to the respective eyeballs.

2. A head for dolls comprising a pair of eyeballs independently journaled therein, a generally 45 U-shaped helically wound spring having its end portions mounted in the respective eyeballs, and a counterweight mounted on said spring between the ends thereof.

3. A doll head consisting of flexible material 50 formed with eye openings, a circular wall circumscribing each eye opening internally of the head and defining a socket, a tubular metal thimble seated in each socket, each thimble being formed with an inturned end-flange disposed behind the flexible material adjacent the eye, to 55

- reinforce said material, pivot rods supported at their ends in opposite walls of said thimbles, eyeballs journaled on said pivot rods, and a counterweight connected to each of said eyeballs.
5. 4. A combination as defined in claim 3 in which the counterweight is connected to the eyeballs by resilient material.
5. 5. A rubber doll head including an eye opening and an inwardly projecting rubber casing at the 10 eye opening, said casing being generally cylindrical and being open at the rear or inner end thereof to facilitate insertion therein of a movable eye assembly from within the head.
- 10 6. A flexible doll head formed with a pair of 15 eye openings and an inwardly projecting integral
- casing at each eye opening, and individual rigid socket members retained by the casings, said socket members pivotally supporting individual eye members mounted for relatively independent but simultaneous operation.
5. 7. A flexible doll head formed with a pair of eye openings and an inwardly projecting integral casing at each eye opening, and individual rigid socket members retained by the casings, each socket member having an eye member pivotally mounted for movement therein, a flexible member for connecting said eye members to each other and gravity operated means for controlling movement of said eye members.
